UNITED STATES PATENT OFFICE.

CLEARENCE B. O'NEILL, OF CLYMER, PENNSYLVANIA.

NONSET AUTOMATIC STOP.

Application filed November 18, 1921. Serial No. 516,171.

To all whom it may concern:

Be it known that I, CLEARENCE B. O'NEILL, a citizen of the United States, residing at Clymer, in the county of Indiana 5 and State of Pennsylvania, have invented a new and useful Nonset Automatic Stop, of which the following is a specification.

This invention relates to graphophone attachments, the primary object of the invention being to provide means for automatically controlling the brake lever of a graphophone to cause the motor to shut off when the reproducer forming a part of the graphophone has reached the innermost 15 groove of a record.

Another object of the invention is to provide a device of this character which may be readily and easily applied to the usual graphophone construction, eliminating the 20 necessity of making elaborate alterations to accomplish the installation of the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 30 within the scope of what is claimed, without departing from the spirit of the invention.

Referring to the drawings:

Figure 1 is a side elevational view disclosing a portion of a phonograph turn-table and illustrating the invention as applied.

Figure 2 is a fragmental plan view of a turn-table, the same being partly broken away to disclose the brake lever.

Figure 3 is a sectional view taken on line 3—3 of Figure 1.

Figure 4 is a rear elevational view of a reproducer and tone arm, the turn-table being shown as broken away.

Figure 5 is a side elevational view of the same.

Figure 6 is a fragmental detail view of a record which is formed with a recess portion to cooperate with the stopping device.

Figure 7 is a sectional view taken on line 7—7 of Figure 5.

Figure 8 is a modified form of lever securing means.

Referring to the drawings in detail, the 55 reference character 5 designates the turn-

table of the usual graphophone, which supports the usual record or music tablet. The reference character 6 designates the usual tone arm which carries the reproducer 7, at one end thereof.

The brake arm which cooperates with the turn-table 5 is designated by the reference character 8, the brake arm being of the usual construction and formed with a lateral extension 9 carrying the brake foot 10 designed to engage the turn-table to prevent rotation thereof. This brake arm is normally held under the tension of the coiled spring 11 that has one end thereof connected to the arm 8, the opposite end thereof connected to the lever 12 which is pivotally mounted adjacent to the arm 8.

A lug indicated at 13 extends upwardly from the arm 8 and is engaged by the notched portion of the arm 12 to hold the spring 11 under tension, and retain the foot 10 out of engagement with the turn-table when the turn-table is in operation. Pivotally supported adjacent to the tone arm 6 is an arm 14 which is relatively wide and curved to conform to the curvature of the tone arm 6.

A bracket 15 has pivotal connection with the arm, the bracket being secured to the top of the graphophone cabinet, as clearly shown by Figure 1 of the drawings.

Connecting the arms 12 and 14 is an actuating rod 16 which has an upwardly extending end portion 17 connected to the lug 18, formed integral with the arm 14. Thus it will be seen that movement of the arm 14 produces a relative movement of the rod 16, and arm 12, to release the brake arm 8 to permit the coiled spring 11 to operate the brake arm to shut off the operation of the machine.

Bearing members 19 form a part of the tone arm and are shown as disposed on the under side thereof, the bearing members being designed to receive the reciprocating operating rod 20 which has one end thereof offset and contacting with the arm 14, the opposite end thereof contacting with the pivoted operating lever 21 which is pivotally mounted at one end of the arm 22. A pivoted foot 23 is carried at the lower end of the lever 21, and is formed with a felt covering adapted to contact with the surface of the record or music tablet. This pivoted foot 23 is normally urged rearwardly as by means of the spring 24 which is shown as

having connection with the lever 21 at one end, and bearing against the pivoted foot 23 at its other end.

5 A recess 25 is formed in the record or music tablet at a point adjacent to the central opening thereof, where the same lies within the path of travel of the pivoted foot 23 when the reproducer has moved to the limit of its innermost movement, where-
10 upon the pivoted foot 23 contacts with the walls of the recessed portion.

It follows that when the pivoted foot 23 contacts with the walls of the recessed portion, the pivoted lever 21 is moved to a
15 position as shown by Figure 5 of the drawings, with the result that the operating rod 20 is moved longitudinally of the tone-arm 6 causing a relative movement of the arm 14, and rod 16, releasing the arm 12 and per-
20 mitting the spring to move the brake arm to prevent movement of the turn-table.

The bearing member as shown by Figure 8 of the drawings, includes opposed sections 26 which may be clamped around the tone
25 arm of a phonograph as shown by Figure 8 of the drawings, and held in such position by means of the bolt 27.

Having thus described the invention what is claimed as new is:—

30 1. In combination with the tone-arm, turn-table and music tablet supported on the turn-table, a lever supported adjacent to one end of the tone arm and carrying a pivoted foot contacting with the music tablet,
35 said music tablet having a recessed portion lying within the path of travel of the pivoted foot, a brake arm, means for connecting the lever and brake arm, and said pivoted

foot adapted to contact with the walls of the recessed portion to cause the operation of 40 the lever and connecting means between the lever and brake arm.

2. In combination with the tone arm, turn-table, and music tablet supported on the turn-table, an operating rod carried by 45 the tone arm, a brake arm for controlling movement of the turn-table, means for connecting the operating rod and brake arm to cause the brake arm to stop rotation of the turn-table, a lever supported adjacent to one 50 end of the tone arm and contacting with the operating rod, and means at one end of the lever and normally engaging the music tablet for moving the lever to operate the operating rod.

3. In a device of the character described, an operating rod, an actuating rod, a brake arm, a pivoted arm having connection with the actuating rod and contacting with the brake arm, to normally hold the same out 60 of operation, a pivoted arm having connection with the actuating rod and contacting with the operating rod, a lever carrying a foot, and contacting with the operating rod, and said foot adapted to be moved to cause 65 a relative movement of the operating rod, actuating rod and arm, to release the brake arm.

In testimony that I claim the foregoing as my own, I have hereto affixed my signature 70 in the presence of two witnesses.

CLEARENCE B. O'NEILL.

Witnesses:

JNO. L. LIPFIELD,
E. L. FARNSWORTH.
